LESTER A. WERNERY, OF BROOKLYN, NEW YORK, ASSIGNOR TO UNDERWOOD TYPE-WRITER COMPANY, OF NEW YORK, N. Y., A CORPORATION OF DELAWARE.

SET OF MANIFOLDING-SHEETS.

1,299,643.

Specification of Letters Patent.

Patented Apr. 8, 1919.

Application filed November 9, 1917. Serial No. 201,088.

To all whom it may concern:

Be it known that I, LESTER A. WERNERY, a citizen of the United States, residing in Brooklyn borough, in the county of Kings, 5 city and State of New York, have invented certain new and useful Improvements in Sets of Manifolding-Sheets, of which the following is a specification.

This invention relates to manifolding, 10 particularly where one of the work-sheets is to be used as a statement or periodical bill, and another is to be used as a ledger sheet or leaf, or where for any other purpose superposed work-sheets are to be typewritten 15 in a predetermined relation.

It has been the practice to keep the statement and ledger leaf together during the month or other period which is to be covered by the statement; and each time that a fresh 20 item is to be inserted in the statement, to place the ledger leaf first in the typewriting machine and locate it accurately by means of perforations in the sides of the sheet which are impaled upon registering or collating 25 pins upon the typewriting machine; then the carbon sheet is placed upon the ledger sheet, and finally the statement sheet, (also perforated), is likewise impaled upon the registering pins; the position of the statement 30 sheet upon the ledger leaf being chosen, so that the next line of writing upon the ledger leaf may fold just below the last line typed thereon.

This necessitates the printing of many 35 indicating lines and numbers upon the work-sheets, besides making many or all of the sheets of excess width, particularly the statements, which it is desirable to make narrow, but which it is found necessary to make as 40 wide as the ledger leaves, in order to accommodate the side perforations. When the sheets are removed from the typewriting machine, their relative location is lost, so that time is consumed in repositioning them 45 in the machine for the typing of the next item, at a later date. If it should be attempted to use clips to aid in keeping the statement sheet and ledger leaf together while out of use, it would be found incon- 50 venient, because of the clips, to re-insert the ledger leaf in the loose-leaf ledger back, and to bind the leaf in place; moreover the clips would not pass readily through the rolls of the typewriting machine, rendering the

sheets liable to injury and relative displacement. The necessity of equipping the typewriting machine with impaling pins for registering the sheets is a further expense and objection. Moreover, in many instances, where a customer has been accustomed to 60 using unperforated work-sheets according to old methods, he usually has a large stock of such sheets, and it is found difficult to arrange for a re-stocking with perforated sheets, and hence difficult to induce him to 65 adopt typewriting methods for bookkeeping purposes. In addition, it is found in practice difficult or impossible to manufacture the sheets with the perforations made there- 70 in with sufficient accuracy.

The principal objects of my invention are to avoid the labor of collating the sheets in the typewriting machine, and the expense and waste of punching the sheets for collating purposes and of equipping the machine 75 with collating pins, and to avoid the necessity of using extra wide statement sheets, and also to avoid trouble in keeping each statement with its associated ledger leaf together, and further to overcome the various 80 other difficulties mentioned.

Other features and advantages will hereinafter appear.

In the accompanying drawings, 85 Figure 1 is a perspective view of sheets assembled in an illustrative way according to my invention, and placed upon the platen of a typewriting machine.

Fig. 2 is a fragmentary view of a statement having integral separable tongues for 90 attachment to the ledger leaf.

Fig. 3 is a perspective view of a ledger leaf having a statement attached to the face thereof according to my invention, said statement being attached to the bottom portion 95 of the ledger leaf, the upper portion whereof has been filled with lines of items duplicated from a previously written statement.

Fig. 4 is a sectional view to show the relation of the statement, ledger leaf and interposed carbon; the heading of the statement being folded under, and the carbon lying against the face of the ledger leaf throughout.

Fig. 5 is a view similar to Fig. 4, but 105 showing the parts in the relation seen at Fig. 3; the lower portion of the statement being also folded up under the body of the same,

for convenience in binding the leaf in the loose-leaf binder with its statement attached.

Fig. 6 is a view of a form of attachable tongue that may be used in attaching the statement sheet to the face of the ledger leaf, the corner of the tongue being turned up to disclose the gum upon a portion of the under face thereof.

In carrying out my invention, I employ a ledger leaf or sheet 10 of usual form, but preferably omitting the side margin perforations, as well as the usual lines and numbers associated with said perforations; said sheet having the usual means 10^a for binding purposes. The invoice or statement sheet 11 may be much narrower than the ledger sheet, which is an advantage, because it may be so narrow as not to receive thereon the typed amount of the old balance, which is usually typewritten upon the ledger sheet; and it may also be so narrow as not to receive the number folio and other data which are not necessary or not desired upon a statement or invoice. Moreover the reduction in width decreases the cost.

Upon the statement I place preferably at each side a projecting tongue 12, which has upon its under face a gum or adhesive material 13, so that the tongues may be moistened and gummed directly upon the face of the ledger leaf, as shown, thereby securing the statement sheet thereto, so that their relation is fixed for all typewriting purposes, regardless of the length of the period or periods during which the sheets are kept attached together, and regardless of the number of items placed upon the statement, or the number of times that the attached sheets are inserted in the typewriting machine. Moreover, the attached sheets pass readily between the rolls of the typewriting machine.

Where the statement or invoice has a heading 14, the tongues may be placed at the sides of the sheet just below the heading, and the sheet may be folded to bring the heading beneath the body of the sheet out of the way, Figs. 1, 3, 4, 5. The statement sheet may have vertical rulings, dividing it into columns to match columns upon the ledger leaf. The carbon sheet 15 may be inserted with its face next to the ledger leaf, and underlying all the typewriting field upon the statement sheet. The carbon may be removed after each entry is made upon the statement. In this manner, the statement and ledger sheets may be kept together and inserted into the typewriting machine and removed as many times as may be required, without the necessity of re-collating them every time, thus effecting a saving of time. Moreover, the ledger leaf with its attached statement may be readily inserted and bound with other leaves in the ledger.

After the termination of the period for

which the statement is written, or after the statement is full, it may be detached by separating it from its tongues, which may remain attached to the face of the ledger sheet, as at 12^a, where they are so small as 70 to be inconspicuous and unobjectionable. For convenience in detaching the invoice or statement, the tongues may be separated therefrom by a line of perforations 16, or other weakened line. Some of the columns 75 on the ledger leaf are typed with items that do not appear upon the statement; and it will be understood that some of the type impressions may fall upon these tongues without objection, since they may remain permanently gummed to the ledger leaf.

During the next month or other period, it may be necessary to begin a fresh statement for the same customer, at a point just below the entries 17 already made upon the 85 ledger leaf, and this may be done with facility, because the tongues permit the statement to be attached to the ledger leaf at any point down the page, and hence any desired collation or registration of the two sheets 90 may be secured. In case, during the writing of the second or third statement for the same page of the ledger, it should be found that the statement should project at its bottom beyond the lower edge of the ledger sheet, or 95 beyond its lower margin line, the statement may be folded up at the bottom, as at 18, Figs. 3 and 5; the carbon 15 always remaining under the folded parts of the statement.

It will be perceived that the ledger leaf 100 with the statement attached thereto may be inserted in the typewriting machine and accurately positioned with reference to the printing line, by the use of a registering table, illustrated in the McCormack Patent 105 No. 829,989, and that then the manipulation of the platen may proceed in the usual manner, so that the two sheets may be positioned even more accurately in the machine than has heretofore been the case where perforations and impaling pins have been resorted to, and without the trouble, expense and delay arising from the use of perforations.

The tongues may be integral with the outer sheets, as at 12^b, Fig. 2, being formed 115 by trimming away side portions of the sheet, the under sides of these tongues being gummed; or other integral tongues may be formed within the scope of the invention. In other views, the tongues are shown as being formed separately and attached to the statements; each tongue being gummed at 13 upon one side thereof along one border of the median line of perforations 16 and upon the other side thereof at 19 along the 125 other border of said line. Other forms of attachable tongues may also be employed.

Variations may be resorted to within the scope of the invention, and portions of the improvements may be used without others.

Having thus described my invention, I claim:

1. The combination with a main sheet having a form printed thereon, of an auxiliary sheet having a corresponding form printed thereon and provided with projecting tongues, whereby it is secured upon the face of the main sheet with the forms registering, said projecting tongues being gummed upon their under surfaces for attachment to the main sheet.
  2. The combination with a main sheet having a form printed thereon, of an auxiliary sheet having a corresponding form printed thereon and provided with projecting tongues, whereby it is secured upon the face of the main sheet with the forms registering, said projecting tongues having weakened lines at their junctions with the auxiliary sheet, to permit the auxiliary sheet to be removed while the tongues remain permanently upon the main sheet.
  3. The combination with a ledger leaf
- provided with binding means, of a statement or invoice sheet of substantially less width than the ledger leaf, said statement provided with laterally projecting tongues whereby it is gummed upon the face of the ledger leaf, and said tongues being separated by weakened lines from the statement sheet.
4. The combination with a ledger leaf provided with binding means and having a form printed thereon, of a statement or invoice sheet of substantially less width than the ledger leaf and having a corresponding form printed thereon, said statement having a heading which is folded under, and also having laterally projecting tongues below said heading, whereby it is gummed upon the face of the ledger leaf.

LESTER A. WERNERY.
